UNITED STATES PATENT OFFICE.

JOSEPH B. BROOME, OF OSWEGO, NEW YORK.

LETTER-BOX.

SPECIFICATION forming part of Letters Patent No. 292,533, dated January 29, 1884.

Application filed May 17, 1883. (No model.)

To all whom it may concern:

Be it known that I, JOSEPH B. BROOME, a citizen of the United States, residing at Oswego, in the county of Oswego and State of New York, have invented certain new and useful Improvements in Letter-Boxes; and I do hereby declare the following to be a full, clear, and exact description of the invention, such as will enable others skilled in the art 10 to which it appertains to make and use the same.

This invention relates to new and useful improvements in letter-boxes, and has for its object to provide for letter-carriers a receptacle to receive letters and papers on their rounds of delivery. This object is accomplished by the device illustrated in the accompanying drawings, forming a part of this specification, in which—

20 Figure 1 is a front elevation of a door provided with my attachments for this purpose. Fig. 2 is a transverse section of a part of a door provided with my attachments, showing the door-plate closed. Fig. 3 is a plan showing the striking machinery of a gong which is to be operated by a cord secured to a door-plate, as shown in Fig. 2. Fig. 4 is a transverse section of a door provided with a modified form of my attachments, showing the door-plate closed, also its position in dotted lines 30 when open.

The letter A represents a door-plate covering an aperture, E, in the door B, for the reception of letters. The plate is hinged at 35 the top, and may be provided with a spring or a catch, Y, to keep it closed. On the inside of the door-plate is an eye, A', to which is attached a cord, D, which is carried through suitable openings in the door B, or directly 40 through the aperture E under the pulleys C C', then upwardly, and attached to a wheel, W, by any suitable means. The opening of the door-plate A for the introduction of mail- 45 matter through the slot E draws the cord D and causes the wheel W to partly rotate upon the stud H and the pin w to strike against the pivoted arm S, thereby causing the block Z to partly rotate on the stud M, to which block Z the arm g of the hammer G is attached. In this manner the hammer G is 50 gradually forced in the direction of the stud H until released by the pin w slipping off

the end of the pivoted arm S, which will occur as soon as the wheel W has been rotated far enough, and when released the hammer G will strike the gong or bell F and cause it to sound the alarm. The arm S is pivoted to the block Z by the pin or rivet R', which also holds a spring, R. This spring R causes the arm S to assume its normal position as soon as the wheel W has carried the pin w beyond the end of the arm S. As soon as the plate A has been closed, so as to assume the position shown in Fig. 2, the wheel W is carried back to the position shown in Fig. 3 by means of a volute spring, Q, which is attached to the under side thereof and to a stud, P. In assuming this position the pin w strikes the arm S, which, being pivoted at R', gives sufficiently to permit the pin w to 60 pass it.

The construction of this device is such that the slot E is concealed from view, and may be secret to all save the carrier.

A box, bag, or other receptacle for the mail may be placed on the inside of the door.

Having described my invention, what I desire to secure by Letters Patent, and claim, is—

1. In combination with a door, B, having slot E, the hinged plate A, having eye A', cord D, and friction-pulleys C C', and wheel W, adapted to operate the striking devices, as shown and described.

2. In a letter-box, the door B, having slot E, the hinged plate A, having eye A', the cord D, attached at one end to eye A' and at the other to wheel W, having pin w, adapted to engage with pivoted arm S and operate the hammer G, the whole in combination, as described, and for the purposes set forth.

3. In a letter-box, the door B, having slot E, provided with friction-rollers C C', hinged door-plate A, having eye A', in combination with cord D, wheel W, pin w, spring Q, and stud P, as described, and for the purposes set forth.

In testimony whereof I affix my signature in presence of two witnesses.

JOSEPH B. BROOME.

Witnesses:

CHAS. T. PLACE,
JAMES B. SPENCER.
